FOREIGN PATENT DOCUMENTS

EM 003255322-0001 * 6/2016

Primary Examiner — Paula Allen Greene(74) *Attorney, Agent, or Firm* — Russell Swerdon; Desmund Gean(57) **CLAIM**

The ornamental design for an audio device, substantially as shown and described.

DESCRIPTION

FIG. 1 is a front perspective view of an audio device showing our new design;

FIG. 2 is a rear perspective view of the audio device in FIG. 1;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in the drawings represent the portions of the audio device that form no part of the claimed design.
